AMUSEMENT-RIDE DEVICE

John P. Von Atzingen, 260 North St.,
Jersey City, N.J. 07307

Filed Oct. 1, 1971, Ser. No. 185,924

Term of patent 14 years

Int. Cl. D21—03

U.S. Cl. D34—5 L

FIG. 1 is a front perspective view of the amusement-ride device embodying the features of my new design;
FIG. 2 is a rear perspective view thereof.

I claim:

The ornamental design for an amusement-ride device, substantially as shown and described.
